UNITED STATES PATENT OFFICE.

GEORGE M. POINT AND CHARLES H. DOEBLER, OF HUNTINGTON, WEST VIRGINIA.

GRINDING-MACHINE.

1,149,288.

Specification of Letters Patent. Patented Aug. 10, 1915.

Application filed December 3, 1912. Serial No. 734,671.

To all whom it may concern:

Be it known that we, GEORGE M. POINT and CHARLES H. DOEBLER, citizens of the United States, residing, respectively, at 833 5 Ninth street and 640 Fifth street, Huntington, in the county of Cabell and State of West Virginia, have invented certain new and useful Improvements in Grinding-Machines, of which the following is a specification.

This invention relates to a grinding machine and one of the principal objects thereof is to provide a machine which will grind, at the same time, a plurality of glasses used 10 in water gages.

Another object is to provide a grinding machine which is efficient in operation and comparatively inexpensive to manufacture.

A further object is to provide a grinding 20 machine whereby lateral and reciprocatory motion is imparted to the object to be ground, by means of eccentrics of different degrees of throw provided upon an identical shaft.

These and other objects may be attained 25 by means of the construction, combination and arrangement of parts hereinafter more fully described, pointed out in the claims and illustrated in the accompanying drawings in which:

Figure 1 is a top plan view of our invention. Fig. 2 is a sectional view thereof taken on the line $x-x$ of Fig. 1 and looking in the direction of the arrows. Fig. 3, is 35 a sectional view taken on the line $z-z$ of Fig. 1.

Referring more particularly to the drawings the preferred embodiment of our invention provides a rectangular table 1, supported in any desired manner. Provided centrally thereof is a perforation through 40 which a shaft 1 extends, the portion of the shaft for a way above the table being fitted with a collar 3, provided at its lower end with an annular flange 4 which rests upon the table 1. The portion of the shaft above the collar is reduced in size and has its upper end screw threaded and provided on the screw threaded 45 portion with a disk 5, said disk being provided near the outer edge thereof with a vertical pin 6. Secured to the reduced portion of the shaft immediately above the collar 3 and resting thereon is a grinding 55 disk, comprising a bottom 7, provided at its outside periphery with an upwardly extend-

ing annular flange 8, and further provided centrally of the bottom 7 with an upwardly extending enlarged portion 9, through which the reduced portion of the shaft 2 extends. 60 The enlarged portion 9 forms, with the flange 8, an annular groove of considerable width and seated in this groove is an annular grinding plate 10, made of any desirable and suitable substance. 65

Detachably secured to each corner of the table 1 by means of a strap 11 and bolts 12 is an angle iron 13, provided with a vertical portion 14, and an inwardly bent horizontal portion 15, said horizontal portion 70 extending over the grinding disk and having its inner end enlarged as at 16 and bifurcated. Pivoted between the prongs of the bifurcated end portion by means of lugs 17 borne in perforations in said prongs is 75 a collar 18, slidably maintaining in position a cylindrical spring casing 19, said casing having its upper end closed and provided centrally of the closed portion with a perforation, through which extends a pivot pin 80 20, having its lower end beveled to a point 21. Near its lower end, the pin is provided with an enlarged portion 22 which fits the inside of the spring casing and is adapted to slide therein. A coiled spring 23 surrounds the pin above the enlargement 22 and bears at one end against said enlargement and at the opposite end against the closure at the top of the spring casing. Secured in any desired manner in the top of the spring 90 casing, such as by being seated in a slot therein is an upright resilient member 24 semi circular in cross section, said member being quite close to the pin 20 but not touching it, and being provided near its upper 95 end with a pair of oppositely disposed notches adapted to engage a cross pin 25 seated in a perforation of the pivot pin 20 a little above the spring casing 19. It will be understood that normally the pin 20 is 100 pressed downwardly by action of the spring 23, but at times it is desirous to maintain this pin in a raised position as will be explained hereinafter, and it is at such times that the cross pin is engaged by the notches. 105 A set screw 26 seated in a screw threaded perforation in the front of the collar 18, is adapted to hold the spring casing 19 in position.

The preferred embodiment of the invention 110 provides a glass holder comprising a narrow plate 27, rounded at each end and

provided with a number of downwardly extending pins 28 arranged to bear against the periphery of a gage glass 29. The upper surface of the plate is provided centrally thereof with a recess 30 of a greater diameter than the diameter of the pivot pin 20, and is drilled out to conform with the point 21. At one end of the glass holder is provided an upwardly extending pin 31.

10 Keyed or secured in any desired manner upon the reduced portion of the shaft 2, above the grinding disk and directly above one another, are four eccentrics 32, each working in an eccentric strap 33. Integral 15 with each strap is an eccentric rod 34, provided at its outer end with a perforation for the passage therethrough of a pin 20. Four rods 35 provided at each end with a perforation are secured at one end on the 20 vertical pin 6, by being slipped onto the pin, and each of the free ends of the rods 35 is slipped on one of the pins 31 on the glass holders 27.

The shaft 2 is provided below the table 1 25 with a bevel gear 36, and meshing with this gear is another gear 37 secured to a shaft 38, driven in any desirable way. The shaft 2 at its lower end terminates in a tapered slot 39, to which if desired an air motor (not 30 shown) may be attached to run the machine after the gear 37 has been disengaged. When the shaft 2 is rotated, the grinding disk and plate are rotated with it thus 35 grinding the glass 29, which is given a reciprocatory movement through the eccentric and eccentric rod 34 which oscillates the pivot pin 20 thus moving the glass back and forth, at the same time that oscillatory motion is imparted to the glass by reason of the 40 movement of the rod 35 extending from the pin 6 to the pin 31 on the glass holder. When it is desired to remove or replace the glass, the pin 20 is raised until the cross pin 25 engages the notches in the member 24, 45 whereby the point 21 of the pivot pin is brought out of engagement with the recess 30 in the glass holder. The rod 35 may then be taken off the pin 31 and the glass holder be easily removed.

50 Although we have described the specific construction, combination and arrangement of parts comprising the preferred embodiment of our device, yet it is to be understood that such minor changes may be made there- 55 in as do not depart from the spirit of the invention and the scope of the appended claims.

Having thus described our invention, what we claim as new and desire to secure by Letters Patent, is:

60 1. In a grinding machine of the kind described, a table, a shaft extending therethrough, a grinding disk on said shaft, a grinding plate on said disk, angle irons

having a portion extending over the grinding plate, spring actuated pins supported by said irons, holders engaged by said pins, said holders adapted to maintain the object to be ground, means for reciprocating the holders and means for oscillating the same, as, and for the purpose, described. 65

2. In a grinding machine, a table, a shaft extending therethrough, a grinding disk on said shaft, spring actuated pivot pins supported above said disk, holders engaged by said pins, eccentrics on said shaft, means connected to said eccentrics and said pivot pins for reciprocating said holders, and means for oscillating the same, as, and for 70 the purpose, described. 75

3. In a grinding machine, a table, a grinding disk supported thereabove, a grinding plate on said disk, spring actuated pivot pins supported above said disk, holders supported by said grinding plate, said holder engaged by said pivot pins, means for holding said pins out of engagement with said holder, means for reciprocating said holders, means for oscillating the same, and means for revolving said disk and plate, 80 as, and for the purpose, described. 85

4. In a grinding machine, a table, a shaft extending therethrough, a grinding disk secured on said shaft, a grinding plate on said disk, a smaller disk on the shaft, a pin in said smaller disk, spring casings supported above said grinding disk, pivot pins in said casings, springs in said casings to normally hold said pins downwardly, holders supported above said grinding plate, and pivotally engaged by said pivot pins, means for holding said pins out of engagement with said holders, pins supported in said holders, rods extending from the last mentioned pins to the pins on the smaller disk for oscillating said holders, eccentrics on said shaft, rods extending from said eccentrics to the pivot pins for reciprocating the holders, and means for revolving the said shaft, as, and for the purposes described. 90 95

5. In a grinding machine, the combination of a revoluble disk, a grinding plate thereon, with pivotally held holders, means for reciprocating the holders, and means for oscillating the same. 100 105

6. A machine of the type described, including a carrying member, means for actuating said carrying member, a holder superposed with respect to said carrying member, means for reciprocating said holder, and means for imparting an oscillatory movement to said holder, said reciprocatory and oscillatory movement transmitting means being actuated from said carrying member actuating means. 110 115 120

7. A machine of the type described, including a carrying member, means for actuating said carrying member, a holder su- 125

perposed with respect to said carrying member, means for reciprocating said holder, and means for delivering resilient pressure to said holder.

- 5 8. A machine of the type described, including a carrying member, means for actuating said carrying member, a holder superposed with respect to said carrying member, means for reciprocating said holder, 0 means for delivering resilient pressure to

said holder, and means for imparting an oscillatory movement to said holder.

In testimony whereof we affix our signatures in presence of two witnesses.

GEORGE M. POINT.
CHARLES H. DOEBLER.
